ASSIGNORS TO THE NORRIE & JUDD MANUFACTURING COMPANY, OF NEW
BRITAIN, CONNECTICUT, A CORPORATION OF CONNECTICUT.

BUCKLE.

1,415,017.

Specification of Letters Patent. Patented May 9, 1922.

Application filed December 6, 1921. Serial No. 520,800.

To all whom it may concern:

Be it known that we, JOHN F. CARPMILL and GEORGE W. TROOP, citizens of the United States, residing at New Britain, in the county of Hartford and State of Connecticut, have invented certain new and useful Improvements in Buckles, of which the following is a specification.

This invention relates to buckles. A buckle embodying the invention can be successfully used in many different connections. It may for example be employed with advantage, for maintaining a strap or web in closed position, when associated for instance with a belt, as in holding school books or in harness and even human wear. Obviously therefore the invention is not limited to the employment of the buckle in any particular field.

Among the objects of the invention are the provision of a buckle which can be inexpensively manufactured, which possesses the necessary strength, and which securely maintains a strap, band or web in closed relation but which can be readily and promptly released.

The article possesses other features of novelty and advantage, which, with the foregoing will be set forth at length in the following description wherein will be described in detail, one of the several forms of embodiment of the invention, which has been selected for illustration in the drawings accompanying and forming part of the present specification. Clearly the invention is not restricted to this disclosure. Departure may be made therefrom, in a number of respects within the scope of the invention defined by the claims following said description.

Referring to said drawings:—

Figure 1 is a perspective view of a buckle involving the invention, showing the same connected with a belt the end portions only of which are shown.

Fig. 2 is a top plan view, and, Fig. 3 is a longitudinal section of the same.

Like characters refer to like parts throughout the several figures.

The buckle desirably involves in its structure a body member, a locker, and a terminal member such as those denoted in a general way, respectively by 2, 3, and 4 and which are usually made from sheet metal or similar material.

The body member shown, has a bottom 5 and practically co-extensive therewith and along opposite sides thereof, the parallel flanges 6, said bottom and side flanges being upon a longitudinal and comparatively slight curve or arch. The side flanges 6 about midway of their length, have the lugs or ears 7 to constitute proper means to support the locker 3 as will be hereinafter described. It should be noted at this point, that the lugs or ears have perforations or holes 8 to receive studs or pivots extending laterally and outwardly from the locker.

The locker 3 as shown has at its forward end portion, the inwardly-extending flange 9 terminating at its inner portion in a rearwardly projecting clamping lip 10, and slightly rounded in cross section to function as a cam. The forward portion of the locker 3 is flat and back of this flat portion is extended or bent inwardly as at 11, the inwardly bent portion being then bent backwardly as at 12 at a comparatively slight angle. Said locker at its forward or inner end has the outwardly extending studs or pivots 13 which are projected through the perforations or holes 8 and are headed exteriorly of the lugs or ears 7. Said locker also has in it the practically rectangular slot 14 which as shown intersects the body or inner portion of the locker and the portions 11 and 12 thereof.

At about the junction of the portions 11 and 12, the locker 3 is provided with a transverse rigid pivot 15 crossing the slot 14 and around which is fitted the eye 16 at the front end of the terminal member 4. We should state that the end portions of the pivot 15 are generally rigid with the locker 3 and that the inner or front end of the terminal member 4 is curved about this pivot which generally consists of a pin. Said terminal member is in the form of a clip and the eye to which reference has been made, is integral with the outer member of the clip and its length is practically equal to the width of said slot 14.

In practice one end of a web or belt is firmly connected with the clip portion of the terminal member 4 which it will be remembered is flexibly connected with the locker 3. This locker 3 has at its forward end portion the inwardly extending flange 9 terminating in a rearwardly projecting

clamping lip 10 which is sufficiently transversely rounded to function as a cam, in pressing the free portion of the belt or web against the body 2. Upon endwise pull on the belt, which is applied to the terminal member 4, the locker 3 is rocked and the backwardly-bent portion 12 is caused to bind against the free end portion of the web or belt and thus aid in clamping the belt. In addition to this, said bent portion 12 functions as a stop to effectually prevent the clamping or cam portion 10 from becoming disengaged from the free end part of the belt or web or as might be otherwise expressed to stop it from going past the holding point.

What we claim is:—

1. A buckle of the class described comprising a body member having parallel flanges along its opposite sides, a locker pivotally mounted between the side flanges and comprising a flat body portion having a depending flange at its forward end terminating in its lower end in a rearwardly extending lip, said body portion also having downwardly and rearwardly extending portions at angles to each other, said locker having a slot extending through its body portion and also through said downwardly and rearwardly extending portions, and a terminal member, for connection with a web, pivotally mounted in said slot.

2. A buckle of the class described comprising a body member having parallel flanges along its opposite sides, a locker pivotally mounted between said side flanges and comprising a flat body portion having a depending flange at its forward end terminating at its lower end in a rearwardly extending

lip, said body portion also having downwardly and rearwardly extending portions at angles to each other, the locker having a slot extending through its body portion and also through said downwardly and rearwardly extending portions, a pivot extending across the slot, and a terminal member having a portion curled about said pivot, for flexible connection with the locker.

3. A buckle of the class described comprising a body member having parallel flanges on its opposite sides, a locker pivotally mounted between the flanges and comprising a flat body portion and a depending flange at its forward end and in turn provided with a rearwardly extending lip to function as a cam, said body portion having downwardly and rearwardly extending portions at angles to each other, said locker having a slot extending through its body portion and also through said downwardly and rearwardly extending portions, and a terminal member, having means for connection with a web, pivotally mounted in the slot, said rearwardly extending portion and said lip acting to engage the web, endwise pull on the web functioning to rock the locker, and the rearwardly extending portion acting to prevent the lip from being disengaged from the free portion of the web.

In testimony whereof we affix our signatures.

JOHN F. CARPMILL.
GEORGE W. TROOP.
